HIGH-FREQUENCY RESISTANCE

Kenneth Eric Latimer, Hendon, London, England, assignor to The Hartford National Bank and Trust Company, Hartford, Conn., as trustee

Application January 8, 1943, Serial No. 471,724
In Great Britain January 9, 1942

9 Claims. (Cl. 201—63)

The present invention relates to electrical resistors and more particularly to electrical resistors suitable for use at high frequencies.

It is already well known to construct resistors intended for use at high frequencies, and more particularly those used for electrical measurements in which it is desired to know accurately the value of the resistance at such high frequencies, in such a way that the unavoidable inductance L_0 and capacity C_0 obey the relation

$$\frac{L_0}{C_0} = R_0^2 \quad (1)$$

where R_0 is the value of the resistance. It is immaterial whether the effective capacity is considered to shunt the resistance alone, or the resistance and inductance, as both arrangements are imperfect representations of the actual conditions. In general such a plan works well enough for frequencies well below the cut-off of the half section of low pass filter represented by L_0 and C_0 , except as regards skin effect which is calculable and can be prevented from having undue influence by the use of suitably thin material.

If the resistor is composed of a coil of wire, the cut-off of the hypothetical filter will generally be quite low. In the most favourable case in which the resistor is a short element of comparatively high resistance material, the cut-off may be raised to a value at which the dimensions of the resistance element become comparable with a wave-length.

The chief object of the invention is to enable a resistance to be constructed in such a way as to have a constant value (apart from skin effects) up to a frequency such that the wavelength may be considerably shorter than the dimensions of the resistor. Apart from obvious constructional advantages, this procedure enables a considerable power to be dissipated in the resistor without damage. It will further be shown that in one embodiment of the invention, the power is dissipated in the resistance element in a uniform manner, which still further raises the allowable dissipation. Another object of the invention is to enable the terminals of the resistor to be brought out in such a way that they are capable of direct connection to a coaxial line of the type used in communication systems.

Let the resistance per unit length of the resistance element be R (where R may possibly be a function of length), then according to the invention the capacity and inductance per unit length of the circuit of which the resistance element forms part (the meaning of the word "circuit" in this connection will be made clear later),

should be so proportioned that at the point x along the length of the resistance element the characteristic impedance

$$z = \sqrt{\frac{L}{C}} = \int_0^x R dx \quad (2)$$

Under these circumstances the circuit containing the resistance element will present a constant resistance at its terminals even if the resistance element is several wave-lengths long.

This relationship will now be justified. Suppose that the resistance element is surrounded wholly or partially by a return circuit in order that both terminals may occur at the same end of the resistance element. A preferred embodiment would be to have the return conductor coaxial with a cylindrical resistance element, but this is not essential. It is further supposed that the dimensions of the resistance element and return conductor are such that there is no appreciable axial component of electric field, i. e., the structure is to be considered comparatively long compared with its own diameter. In some instances it may be desirable to make the return conductor also a resistance element in which case the return conductor is made of a suitable resistance material.

At the end remote from the terminals, the resistance and the return conductor are short circuited together. Take this short circuit as the origin for x , the distance along the resistance element, and at a given distance x consider the increment of impedance added by a length dx of resistance element and return circuit. If the total impedance of the resistance and return conductor at the point x is Z then the impedance at point $x+dx$ can readily be shown to be

$$Z + dZ = \frac{Z + (R + j\omega L)dx}{j\omega CZdx + 1} \quad (3)$$

neglecting higher order terms.

By the binomial theorem, again neglecting higher order terms

$$Z + dZ = Z + (R + j\omega L - j\omega CZ^2)dx \quad (4)$$

Now if

$$L = CZ^2 \text{ or } \frac{L}{C} = Z^2 \quad (5)$$

Then

$$dZ = Rdx \quad (6)$$

$$Z = z \text{ (see Equation 2)} \quad (7)$$

$$= \int_0^x Rdx \quad (8)$$

From this it is readily seen that the total impedance of the element and its return conductor at any frequency will be the ohmic resistance of the element, apart from skin effect.

A particularly desirable solution occurs when 5 R is constant. In this case

$$Z=Rx \quad (9)$$

In this case the return conductor should be 10 made in the form of a logarithmic "horn," in which the throat has the same diameter as, and is connected to, the resistance rod, and the open end has the same internal diameter as that of the outer conductor of a co-axial line to which the resistance is connected. If, however, the outer diameter of the inner conductor of the co-axial line is the same as that of the resistance element, and if the total resistance of the 20 resistance rod, assumed uniform, is equal to the characteristic impedance of the co-axial line, the latter will be smoothly terminated at all frequencies, apart from skin effect. In practice, in order to achieve this, the resistance element may consist of a very thin layer of conducting material applied to the surface of a suitable dielectric, so as to avoid troubles due to skin effect.

The logarithmic relationship arises in the following way. The inductance in electromagnetic units of a coaxial line is

$$2 \log_e \frac{d}{D_1}$$

where D_1 is the outer diameter of the inner conductor and of the resistance rod. 35

d is the inner diameter of the horn at distance x from the end.

The corresponding capacity in electrostatic units is

$$\frac{1}{2 \log_e \frac{d}{D_1}}$$

In the case of the coaxial line attached to the resistance element the same formulae apply except that d becomes D_2 , the inner diameter of the outer conductor of the co-axial line. Since the impedance of an elemental length is thus proportional to the inductance, in fact

$$Z=VL \quad (10)$$

where V is the velocity of light, all that is necessary to satisfy the relationship $Z=Rx$ is to make

$$\log_e \frac{d}{D_1} = \frac{x}{X} \log_e \frac{D_2}{D_1}$$

where X is the length of the resistance rod; also RX must be made equal to the impedance of the co-axial line.

In the above reasoning it has been assumed that the resistance of the return conductor is negligible, so that in the design either the resistance rod must not be made too long, or the finite resistance of the return conductor must be taken into account.

It will now be shown that in the case of the preferred embodiment the dissipation of energy along the rod is uniform.

The equations for the current flowing in the resistance rod are as follows:

If i is the current flowing at point x and i^1 that at $x+dx$ then

$$i^1 = i \frac{1}{Rx + (R+j\omega L)dx + \frac{1}{j\omega Cdx}}$$

Making the usual approximations

$$i^1 = \frac{i}{1 + j\omega CRdx} = i(1 - j\omega CRdx) \quad (11)$$

Substituting for C from (5), (9) and (10),

$$di = i^1 - i = -i \frac{j\omega}{V} dx$$

$$\frac{di}{dx} = -i \frac{j\omega}{V}$$

$$i = i_0 e^{-\left(\frac{j\omega}{V} x\right)} \quad (12)$$

where i_0 is the current at the shorted end of the resistance rod.

The current is thus constant in magnitude throughout the rod although its phase angle is 30 variable. Hence the heating of the rod is uniform considering long time intervals.

By similar reasoning it may be shown that the voltage V to the return conductor at point x is given by

$$V = Rx i_0 e^{-\left(\frac{j\omega}{V} x\right)}$$

a conclusion which may also be reached from 40 (9) and (12).

As a further development the resistance rod may be filled with some fluid having a suitable thermal expansion or alternatively may contain a thermocouple or other means of measuring 45 temperature, in which case the terminating arrangement may serve as a wattmeter to measure the power transmitted along the coaxial line.

The invention will be further described with reference to the appended drawing showing a 50 resistor in accordance with a preferred embodiment of the invention. The resistor there shown comprises a cylindrical core 10 of dielectric material such as electrical porcelain, glass, "Isolantite" or of other ceramic material or may consist of a non-ceramic insulating material such as polystyrene, or the like.

Disposed on the surface of the core 10 and extending to the ends thereof is a resistance element 11 consisting of thin layer or coating of 60 electrical resistance material, for example, a sprayed or adhesively-bonded coating of carbon, or a metal coating of tungsten, platinum, or Monel metal forming a metallized coating on the surface of the core 10. Tungsten can be applied by sputtering, platinum by sublimation, sputtering or sintering, while the Monel metal coating can be produced in situ by electrodepositing copper and nickel separately.

Electrical connection to the ends of the resistance element 11 is obtained by bands 12 and 13 consisting preferably of a coating or plating of low resistance metal such as silver.

Concentrically surrounding the resistance element 10-11 is a metal sleeve 14 which in accordance with a preferred embodiment of the inven-

tion has the shape of a logarithmic horn. A suitable material for the sleeve 14 is brass which has been electrolytically silver plated and rhodium flashed. Any other metal which can be plated in a like manner, can be used. In instances where the sleeve is in itself to form part of the resistance element, it may consist of a thin shell of metal or a molded matrix of carbon suspended in a suitable binder. The throat portion of the sleeve 14 has an internal diameter only slightly larger than the external diameter of the terminal band 13 and is electrically connected to the terminal band by soldering, brazing, or the like.

External electrical connections to the resistor are made in suitable manner to the band 12 and the flared end of metal sleeve 14. In instances requiring that a resistor be connected to a concentric transmission line, the dimensions of the sleeve 14 and the element 10-11 are so chosen that the connecting portions coincide with the outer conductor and the inner conductor respectively of the transmission line.

As above pointed out, the resistor is also suitable for use as a high frequency wattmeter. For this purpose the core 10 may be filled with a fluid having a suitable thermal expansion, i. e. monostyrene or benzene, to which is connected a pressure-measuring instrument calibrated in watts; alternatively, there may be positioned within the resistor element, a thermocouple element connected to a voltmeter calibrated in watts.

While I have described my invention by means of specific examples and in a specific embodiment I do not wish to be limited thereto for obvious modifications will occur to those skilled in the art without departing from the spirit and scope of the invention.

I claim:

1. An electrical resistor comprising an insulating core, a resistance element forming a coating on said core, and an electrically conducting sleeve member surrounding the element, said sleeve being in the form of a logarithmic horn having its throat portion connected to one end of the resistance element, and forming the return conductor for the said end of the resistance element.

2. An electrical resistor comprising an insulating core, a resistance element forming a coating on said core, and an electrically conducting sleeve member surrounding the element, said sleeve being in the form of a logarithmic horn having its throat portion in contact with one end of the resistance element and forming the return conductor for the said end of the resistance element.

3. An electrical resistor comprising an insulating core, a resistance element forming a coating on said core and a sleeve member of electrical resistance material surrounding the element, said sleeve having one end connected to an adjacent end of the resistance element.

4. An electrical resistor comprising a central resistance element and an electrically conducting sleeve surrounding the element and short circuited therewith at one end, the relationship between the characteristic impedance z at a point at a distance x along the element from the short cir-

cuit and R , the resistance per unit length of the element being given by

$$z = \int_0^x R dx$$

5. An electrical resistor comprising a central resistance element and a sleeve member of electrical resistance material surrounding the element, said sleeve being in the form of a logarithmic horn and having the throat portion thereof connected to an adjacent end of the resistance element.

6. An electrical resistor comprising a central resistance element and an electrically conducting sleeve member surrounding the element, said sleeve being in the form of a logarithmic horn having its throat portion connected to one end of the resistance element and forming the return conductor for the said end of the resistance element.

7. A termination impedance for an ultra-high frequency communication system consisting of two concentric elements, one element being tubular and supporting a conducting shell to constitute a resistance element; and the second element being of electrically conducting material and encircling the tubular element short-circuited to one end of the conducting shell, the diameter of the inner surface of the encircling element in a plane transverse to the inner element being equal to

$$D e^{\frac{x}{l}} K$$

35 where D is the outer diameter of the conducting shell on the inner element, l the length of that shell, x the distance from the short-circuited end to the transverse plane locating the diameter, and K a constant representing the natural logarithm 40 of the ratio of the maximum diameter of the encircling element to the diameter of the tubular shell.

8. A termination impedance as described in claim 7 in which the tubular element includes an 45 energy-transfer medium to aid the conducting resistance shell to dissipate a substantial quantity of energy supplied from the system.

9. A termination impedance for an ultra-high frequency system, comprising an insulating tubular core; a resistance element forming a coating on said core; and an electrically conducting sleeve member concentrically surrounding the resistance element, said sleeve being in the form of a logarithmic horn having its throat portion in 55 short-circuit contact with one end of the resistance element and forming the return conductor for that end of the resistance element, the logarithmic form of the horn following the equation

$$d = D_1 e^{\frac{x}{l}} K$$

60 where d is the varying diameter of the horn, D_1 is the outer diameter of the resistance element, and l is its length, x is the independent variable 65 representing the distance along the resistance, and K is a constant; and means for connecting the impedance to an external line.

KENNETH E. LATIMER.
